UNITED STATES PATENT OFFICE.

FREDERICK CARDER, OF CORNING, NEW YORK, ASSIGNOR TO CORNING GLASS WORKS,
OF CORNING, NEW YORK, A CORPORATION OF NEW YORK.

DESIGN FOR A GLASS TEAPOT.

Application filed May 11, 1922. Serial No. 2,191. Term of patent 3½ years.

To all whom it may concern:

Be it known that I, FREDERICK CARDER, a citizen of the United States, residing at Corning, in the county of Steuben, State of New York, have invented a new, original, and ornamental Design for Glass Teapots, of which the following is a specification, reference being had to the accompanying drawing, forming part thereof.

The figure is an elevation of a teapot, showing my new design.

I claim:—

The ornamental design for a glass teapot, as shown.

FREDERICK CARDER.
